UNITED STATES PATENT OFFICE.

ALEXANDER ARTHUR, OF YOUNGSTOWN, OHIO.

OPEN-HEARTH-FURNACE DEVICE.

1,414,451.

Specification of Letters Patent. Patented May 2, 1922.

Application filed February 7, 1921. Serial No. 443,001.

To all whom it may concern:

Be it known that ALEXANDER ARTHUR, citizen of the United States of America, residing at Youngstown, in the county of 5 Mahoning and State of Ohio, has invented certain new and useful Improvements in Open-Hearth-Furnace Devices, of which the following is a specification.

This invention relates to what is commonly known as open hearth furnaces, and to furnaces of like nature.

Furnaces of this type employ opposed gas nozzles and opposed air passages, the products of combustion, after passing through 15 the hearth chamber, being drawn off through both the air passages and the gas nozzle. It is common to provide such a furnace with a reversing gear so that for a desired length of time the gas and air are taken in at one 20 end of the furnace and the products of combustion escape through the air passages and gas nozzle. Then the furnace is reversed and the intake end becomes the outlet end, etc.

25 The principal object of my invention is to utilize the ordinary method of air feed above the gas port and at the same time use a supply of preheated air, and mixing this air with the gas in the port.

30 Another object is to provide a means of utilizing the waste heat carried out with the products of combustion at the outlet end. In order to do this I have provided a two-way tortuous passage in the division wall 35 which separates the gas slag pocket and the air slag pocket. This division wall becomes very hot and by bringing air into this passage the air becomes heated and is then carried through two upward passages through 40 the side walls of the gas port and is mixed with the gas in the port.

Another object is to provide a means of lengthening the life of the division and outer walls.

45 A still further object is to provide a means of reversing the incoming air in said tortuous passage so that the two passages are alternated in their use, thus allowing one passage to become heated to a greater 50 degree by the out-rushing products of combustion than would result from the use of a single tortuous passage.

With the foregoing and other objects in view which will appear as the description proceeds, the invention resides in the combination and arrangement of parts and in

the details of construction hereinafter described and claimed, it being understood that changes in the precise embodiment of the invention herein disclosed, can be made 60 within the scope of what is claimed, without departing from the spirit of the invention.

In the accompanying drawings the preferred form of the invention has been shown. 65

In said drawings: —

Figure 1 is a sectional view of an end of an open hearth furnace showing the two tortuous passages in the division wall, and the passages leading into the side walls of 70 the gas port.

Figure 2 is a sectional view of an end of an open hearth furnace showing the division wall, and side of gas port.

Referring to the drawings in which the same reference characters relate to the same or corresponding parts in all the views, 1 represents the division wall which separates the gas slag pocket 2 from the air slag pocket 3. 4 represents a base portion which may be made of ordinary brick. The side walls 5 may be constructed of the same material. The inner walls 6 and the division wall 1 should be constructed of silica brick or any suitable material having the property of withstanding great heat. 7 represents an ordinary chill box located under the port 8. This chill box 7 is covered with a brick construction 9 and over this the furnace lining material 10. 85

90 By referring to Figure 1 it will be seen that I have provided a fan 11 provided with a valve 12. Leading from this fan 11, I have provided a tube 13 for carrying the air to the tortuous paths 14 and 15. The drawing shows a valve 16 set so that the air enters the tortuous path 14 and this air and the division wall 1 are subjected to great heat when the products of combustion are escaping on either side of the division wall 1 when the port at the opposite end of the furnace is used as the exit. Now the heated air passes through the air passages 17 which leads to and through the two sides of the port 8 at openings 18 where the incoming gas and air are mixed before entering the furnace. The gas is led into the port in the ordinary way through a passage 19. 100

110 In an ordinary furnace the air is led into the furnace above the port 8 and this feature of admitting air is employed in my device, that is, the air entering through the

passage 20 and over the port 8, into the space 21 above the port 8.

Now when the valve 16 is turned up against the end 22 of the tortuous path 14 5 the air enters the tortuous path 15. The object in using a plurality of tortuous paths for the air is to utilize to a greater degree the heat that would otherwise be wasted. In order to utilize this waste of heat in 10 this manner the air is carried first through one tortuous path and the next time through the other tortuous path. The openings 23 may be closed if desired, or used to insert 15 a pyrometer, or to carry into the port 8 other fuels.

By mixing the heated air with the gas in the port 8 a better combustion takes place and at a point in the furnace near the end of the port 8 while the air that enters in 20 the ordinary way above the port 8 is at the same time utilized. One of the objections to the method of using air coming from above the port is that the intense heat of combustion which takes place far into the

furnace causes a great heat at the exit end 25 of the furnace, which is detrimental to the furnace.

Having thus described my invention what I claim is:

1. In a device of the class described, a 30 partition wall separating a gas slag pocket and an air slag pocket, said partition wall provided with a plurality of tortuous paths, an air passage leading from said tortuous paths to an opening on each side of a gas 35 port, means for alternating said tortuous paths, substantially as described.

2. In a device of the class described, a fan, a tube, leading to a plurality of tortuous paths located within a partition wall, air 40 passages leading to an opening on each side of a gas port, substantially as described.

In testimony whereof I affix my signature.

ALEXANDER ARTHUR.
